UNITED STATES PATENT OFFICE.

FREDERICK LELAND DAVIDSON, OF HALIFAX, NOVA SCOTIA, CANADA.

DISH-WASHING MACHINE.

1,360,192.

Specification of Letters Patent. Patented Nov. 23, 1920.

Application filed November 9, 1918. Serial No. 261,846.

To all whom it may concern:

Be it known that I, FREDERICK LELAND DAVIDSON, a subject of the King of Great Britain, and resident of the city of Halifax, 5 in the Province of Nova Scotia, Dominion of Canada, have invented certain new and useful Improvements in Dish-Washing Machines, of which the following is a specification.

10 This invention relates to improvements in dish washing machines of a type in which the plates are held in racks and washed by water splashed against them by a rotary splasher, and the objects of the invention 15 are generally to improve the construction of the device to enable the various parts to better perform the functions required of them.

The invention comprises a casing containing a special form of tray for the plates or dishes, a rotary splasher therein, a hinged cover and hinged brackets adapted to support the cover, constructed and arranged as shown in detail in the accompanying specification and drawings.

In the drawings:

Figure 1 is a longitudinal sectional elevation of the invention.

Fig. 2 is a transverse section.

30 Fig. 3 is a sectional detail showing the water-tight joint between the cover and the casing.

Fig. 4 is a detail of one of the hinged brackets in plan.

35 Fig. 5 is a perspective view of the plate tray.

Fig. 6 is a plan view of the plate tray.

Fig. 7 is an end elevation of the plate tray.

40 Fig. 8 is a detail in plan of a portion of the plate tray.

Fig. 9 is a detail in section of a portion of the plate tray.

45 Fig. 10 is an end view of an alternative form of the plate tray.

Fig. 11 is a plan view of the alternative form of plate tray.

Figs. 12, 13, and 14 show details of the alternative form of the plate tray.

50 Like characters of reference indicate corresponding parts in all the figures.

Referring to the drawings, A represents a casing adapted to contain the dishes to be washed, supported on suitable legs 10 and 55 provided with a cover 11 to make water-tight connection between the front wall 12

to the casing and the edge of the cover, a rabbeted joint is formed between the two and the cover is provided with a beading or bar 13 adapted to fit the end face of the 60 front wall of the casing.

The bottom of the casing is formed with an inclined portion 14 terminating in a partially cylindrical portion 15 provided with a drainage outlet pipe 16. B represents the 65 rotary splasher in any convenient form having its axle 17 supported at one end by a diagonally extending cross bar 18 and having the other end extending through and journaled in the casing and provided with a 70 pinion 19 which meshes with a gear 20 mounted on a shaft 21 adapted to be turned by a handle 22.

The cover 11 is adapted to form a support for the dishes taken out of the casing and 75 to support the cover in this position. One or more hinged brackets 23 are provided hinged to the casing, adapted to be swung outwardly as shown in Figs. 2 and 4 to form a support for the cover, the normal position being indicated in dotted lines in Fig. 4.

To one side of the splasher B is mounted plate holder C, the special design of which is shown in Figs. 5 to 9. The plate holder comprises a base plate 30 suitably supported 85 from the frame, a plurality of plate racks 31, comprising parallel wires 32 and 33 of inverted U-shape, each wire having one end secured to a cross bar 34 on the base, while the other ends are connected together and 90 secured to a movable reciprocating bar 35. The two elements 32 and 33 are preferably made from a single piece of wire the free ends of which are connected to the bar 34 while the opposite ends of the elements 31 95 and 32 are connected by a cross piece or bend 36. The cross bar 35 is adapted to be reciprocated by means of a hinged operating rod 36 extending through an opening 37 in the casing having its ends secured to a projection 38 which connects with a pin 39 extending through a slot 40 in the face 30 and then connected to the cross bar 35, in this way, while one end of each plate rack is held.

100 the other end may be reciprocated to cause 105 opposite sides of the plate to be thoroughly washed. The effect of this is to change the angle of the plate so that first one side of the plate and then the other may be presented to the splashing fluid.

110 Above the splasher is another plate rack D similar in form to the plate rack C and

including the base plate 50 and a plurality of transversely extending racks 51 each including upwardly diverging side members 52 and 53 and cross members 54 adapted to 5 extend across the face of the plates, the lower edge of the plates being adapted to fit against spaced projections 55 on reciprocable bar 56 which is reciprocated by an operating rod 57, the amount of reciprocation being 10 limited by means of a pin 58 which reciprocates in a slot 59 in a base plate 50. In this way the inclination of the plates may be changed to cause opposite sides to be washed.

As many changes could be made in the 15 above construction and many apparently widely different embodiments of my invention within the scope of the claim, constructed without departing from the spirit

or scope thereof, it is intended that all matter contained in the accompanying specification and drawings shall be interpreted as 20 illustrative and not in a limiting sense.

What I claim as my invention is:

In a dish washing machine a plate holder comprising a base plate and reciprocable 25 bar thereon, and a plurality of racks of inverted U-shape each having one end connected to the base plate and the opposite end connected to the reciprocable bar.

In witness whereof I have hereunto set 30 my hand in the presence of two witnesses.

FREDERICK LELAND DAVIDSON.

Witnesses:

M. DUDDY,
CHAS. MURRAY.
